ENGINE STARTER

Kenneth F. Douglas, Elmira, N. Y., assignor to
 Bendix Aviation Corporation, a corporation of
 Delaware

Application March 29, 1946, Serial No. 658,019

4 Claims. (Cl. 74—7)

1

The present invention relates to engine starters and more particularly to means for defining the idle position of a starter drive pinion and insuring traversal thereof upon energization of the starting motor.

It is an object of the present invention to provide a novel starter drive embodying unitary means for defining the idle position of the drive pinion, for assuring traversal of the pinion when the starting is energized, and for preventing rebounding of the pinion when it is thrown back to idle position by the self-operation of the engine.

It is another object to provide such a device incorporating a re-entry spring for assuring traversal of the starter pinion out of idle position and novel retaining thimbles for said spring.

It is another object to provide such a device in which the retaining thimbles for the re-entry spring can be used interchangeably at either end of the spring, the thimble at the rear of the spring being held in place by interlocking means in the nature of a bayonet joint.

It is another object to provide such a device which is economical to manufacture and which may be easily and quickly assembled and disassembled.

Further objects and advantages will be apparent to those skilled in the art from the following description taken in connection with the accompanying drawing, in which:

Fig. 1 is a side elevation partly in section of a preferred embodiment of the invention showing the parts in idle position;

Fig. 2 is a section taken substantially on the line 2—2 of Fig. 1 illustrating the locking mechanism for the thimble;

Fig. 3 is a detail in perspective of one form of retaining thimble for the re-entry spring;

Fig. 4 is a detail in side elevation of the retaining thimble illustrated in Fig. 3, partly broken away to show one of the anchoring studs therefor; and

Fig. 5 is a detail in elevation of a modified form of retaining thimble.

In Fig. 1 of the drawing, there is illustrated a power shaft 1 which may be the armature shaft of a starting motor not shown. Shaft 1 has a reduced extension 2 providing an abutment shoulder 3 against which a thrust ring 4 is preferably seated. An actuating member in the form of a hollow shaft 5 is fixed to the outer end of the power shaft 1 by any suitable means such as a cross pin 6. Shaft 5 is threaded for a portion of its length as shown at 7, and has a smooth

2

reduced intermediate portion 8. An engine driving member in the form of a pinion 9 is slidably journaled on the power shaft between the shoulder 3 and screw shaft 5 for traversal into and out of mesh with an engine gear 11.

Means for actuating the pinion 9 from the screw shaft 5 is provided comprising a control nut 12 on the screw shaft and a yielding driving connection including a block 13 of elastically deformable material such as rubber seated on the control nut 12 against a radial flange 14 formed thereon, and bearing at its forward end against the radial flange 15 of a thimble 16 which is suitably attached as by welding to a flange member 17 rigidly mounted on the pinion 9 as indicated at 18. The rubber block 13 is preferably held under initial compression by means of a barrel member 19 surrounding the rubber block, having an internal shoulder 21 at its rear end engaging the flange 14 of control nut 12, and being provided with an annular internal recess 22 at its forward end in which the peripheries of the flanges 15, 17 are received and retained in any suitable manner as by spinning over the end of the barrel as shown at 23.

The control nut 12 is counterbored in its forward end as shown at 24 so that when the pinion is in idle position as illustrated, it has run off the ends of the threads 7 on the screw shaft and bears rotatably on the smooth portion 8 thereof. Means for yieldably retaining the control nut in idle position is provided comprising a pin 25 mounted in the control nut with freedom for radial movement, and a spring ring 26 pressing the pin into frictional contact with the screw shaft 5, the latter being preferably provided with a shoulder 27 so positioned as to be engaged by the pin immediately after the threads of the nut have entered the thread spaces of the screw shaft.

According to the present invention, unitary means are provided for applying yielding pressure to the control nut 12 to assure entry of the threads thereof into the thread spaces of the screw shaft, which means also serves to arrest the backward movement of the control nut with its associated parts when the pinion is thrown out of mesh as the engine starts, and to apply a frictional retarding effect to said parts while they are overrunning the screw shaft. As here shown, this means comprises a thimble 28 slidably mounted on the rear end of the screw shaft, having a radial flange 29 adapted to be engaged by the adjacent end of the control nut 12, longitudinal movement of the thimble to the right in Fig. 1 being limited by a shoulder 31 on the

screw shaft engaging the inturned end 32 of the thimble. A similar thimble 33 is also mounted on the end of the screw shaft reversely to the thimble 28, and a compression spring 34 is mounted on said thimbles between the flange 29 of thimble 28 and a similar flange 35 on thimble 33.

The thimble 33 is retained on the end of the screw shaft 5 by a quickly detachable connection in the nature of a bayonet joint. For this purpose, a plurality of studs 36 are seated in the end of the screw shaft, projecting therefrom sufficiently to bear loosely within the thimble 33, and the latter has an inturned flange 37 provided with slots 38 arranged to permit the thimble to be slid over said studs, and with depressions 39 intermediate said slots adapted to form seats for receiving said studs when the thimble is rotated to bring the seats into registry therewith. The inturned flange 32 of thimble 28 is similarly formed with slots and depressions in order to permit assembly of the thimble over the studs 36, and to make the thimbles completely interchangeable.

In assembling this drive, the control nut with its associated parts is first mounted on the screw shaft, the screw shaft is placed on the power shaft 1 and anchored thereto by the pin 6, the thimble 28 is then slid on the end of the screw shaft, spring 34 placed thereon and thimble 33 pressed over the studs 36 and rotated until the latter seat in the depressions 39. The thimble 33 then serves to lock the pin 6 and the studs 36 in position, and the pressure of the spring 34 holds the thimble against the studs so as to prevent rotation of the thimble on the screw shaft.

The dimensions of the parts are such that the spring 34 presses the control nut 12 into initial engagement with the threads of the screw shaft 5, further expansion of the spring being limited by engagement of the flange 32 of thimble 28 with shoulder 31 on the screw shaft, which engagement occurs at about the same time that the anti-drift pin 25 in the control nut engages the shoulder 27 of the screw shaft.

In operation, starting with the parts in the positions shown in Fig. 1, rotation of the power shaft 1 causes the control nut 12 to be traversed to the right, causing the pinion 9 to mesh with the engine gear 11, and when longitudinal movement of the pinion is arrested by engagement with the thrust collar 4, the rubber block 13 is compressed and torqued to yieldably transmit the power of the starting motor to the engine gear. When the engine starts, the acceleration of the pinion 9 is transmitted to the control nut 12, which is accordingly thrown back to idle position, running off the ends of the threads 1 of the screw shaft. The impact of the control nut and the parts associated therewith is cushioned by the spring-pressed thimble 28, and the energy of rotation of the parts is dissipated by the frictional engagement of the nut and thimble so as to eliminate any tendency of the parts to rebound. Thereafter, the parts are retained in idle position by means of the anti-drift pin 25.

Although but one embodiment of the invention has been shown and described in detail, it will be understood that other embodiments and adaptations are possible without departing from the spirit of the invention as defined in the claims appended hereto.

What is claimed is:

1. In an engine starter, a power shaft, a hollow shaft threaded for a portion of its length fixed on the power shaft, a pinion slidably journaled on the power shaft for movement into and out of mesh with a gear of an engine to be started, means for actuating the pinion from the screw shaft including a control nut threaded on the screw shaft and arranged to run off the threaded portion thereof when the pinion is demeshed from the engine gear, and means for urging the control nut into initial engagement with the threads of the screw shaft including a thimble having a limited sliding engagement with the screw shaft and adapted to engage the control nut, a compression spring supported at one end on said thimble, a second thimble mounted on the screw shaft supporting the other end of the spring, and means providing a bayonet connection between the second thimble and the screw shaft so positioned as to maintain the spring under initial compression.

2. An engine starter as set forth in claim 1 in which said bayonet connection comprises a plurality of studs mounted in the screw shaft, said second thimble having an equal number of slots adapted to register with the studs during assembly of the parts, to permit passage of the thimble over the studs, said thimble also having an equal number of depressions intermediate the slots adapted to receive the studs and lock the parts together.

3. An engine starter as set forth in claim 1 in which said bayonet connection comprises a plurality of studs mounted in the screw shaft, said second thimble being formed to surround the studs and hold them in the screw shaft.

4. In an engine starter, a power shaft, a hollow screw shaft mounted thereon, a pin anchoring the screw shaft on the power shaft, a pinion slidably mounted on the power shaft, actuating means for the pinion including a control nut having a threaded connection with the screw shaft, and yielding means for initiating longitudinal movement of the control nut on the screw shaft comprising a spring and a thimble forming a seat therefor, studs in the screw shaft for locking the thimble thereon, said thimble being arranged to surround and prevent radial movement of said cross pin and studs.
